CLAIM

The ornamental design for a pet hair cleaning tool, as shown and described.

DESCRIPTION

FIG. 1 is an exploded perspective view of a pet hair cleaning tool embodying our new design, shown with a portion of the cleaning head's protective covering partially peeled back;

FIG. 2 is a front elevational view thereof in the assembled condition, the rear being a mirror image of the front shown in FIG. 2;

FIG. 3 is a rear elevational view thereof;

FIG. 4 is a side elevational view thereof;

FIG. 5 is a top plan view thereof; and,

FIG. 6 is a bottom view thereof.

The handle is shown broken away to indicate indeterminate length.

FIG. 2

FIG. 3

FIG. 6

FIG. 5
